CHRISTMAS TREE ORNAMENT

Joseph L. Doan, Jr., Cynwyd, Pa.

Application July 9, 1956, Serial No. 42,185

Term of patent 14 years

(Cl. D29—1)

Fig. 1.

Fig. 2

Fig. 3

The design is characterized by a head part as shown formed of a cork or other cylindrical body to which are affixed the eyes and nose of the figure, as well as the beard formed of fibrous material, the head part being fitted with a conical head-piece or hat formed of suitable sheet material, such as paper or the like, crowned with tuft of cotton, the whole being supported by a hanger wire extending upwardly through the apex of the head-piece.

I claim:

The ornamental design for a Christmas tree ornament, substantially as shown and described.
